UNITED STATES PATENT OFFICE.

JOHN BOLAND, OF CULEBRA, CANAL ZONE.

HAT-PIN RETAINER.

1,075,689.

Specification of Letters Patent. Patented Oct. 14, 1913.

Application filed November 25, 1912. Serial No. 733,451.

To all whom it may concern:

Be it known that I, JOHN BOLAND, a citizen of the United States, residing at Culebra, Canal Zone, have invented certain new and useful Improvements in Hat-Pin Retainers; and I do declare the following to be a full, clear, and exact description of the invention, such as will enable others skilled in the art to which it appertains to make and use the same.

This invention relates to improvements in hat pin retainers.

One object of the invention is to provide a hat pin retainer adapted to be adjustably secured to a hat pin and to be engaged with the crown of a hat whereby the pin is securely held against casual removal from the hat but may be readily removed therefrom when desired.

With this and other objects in view, the invention consists of certain novel features of construction, and the combination and arrangement of parts as will be more particularly described and claimed.

In the accompanying drawings: Figure 1 is a vertical cross sectional view through a hat showing the application of the invention; Fig. 2 is an enlarged horizontal section through a portion of one side of the hat crown and through the pin receiving member therein, showing a portion of the pin inserted therethrough and the pin retainer in engagement therewith and with the pin; Fig. 3 is a vertical sectional view through a part of the hat crown and the pin receiving member, showing a portion of the pin engaged therewith, and a side view of the pin retainer applied to the pin and in engagement with the pin receiving member; Fig. 4 is a view of the opposite side of the pin and retainer from that shown in Fig. 2; Fig. 5 is a side view of the retainer similar to that shown in Fig. 3 and illustrating the position of the pin gripping members of the retainer when the pin is disengaged therefrom; Fig. 6 is a cross sectional view of the retainer taken on the line 6—6 of Fig. 3.

Referring more particularly to the drawings 1 denotes the hat to which my improved pin receiving and retaining mechanism is applied. At a suitable position in one side of the crown of a hat is formed an opening with which is engaged an eyelet 2 which is preferably formed of metal hav-

ing on its outer end a retaining flange 3 and on its inner end a clenching flange 4 which is formed by slitting and upsetting the inner end of the rivet against the inner side of the hat crown as clearly shown in the drawings. Secured in any suitable manner to the inner side of the hat crown opposite to or in line with the eyelet 2 is a strip or piece 5 of cork or other suitable material which is adapted to receive the point of the pin when the latter is projected through the eyelet and through the hair on the head of the person wearing the hat. By providing the eyelet 2 and the pin receiving strip 5 it will be seen that the necessity of puncturing the crown of the hat each time the pin is applied thereto is obviated as the pin may be readily inserted through the eyelet and the point of the pin engaged with the strip 5 as will be readily understood.

In order to positively hold the pin in engagement with the hat crown and to limit the inward movement of the pin when the point has been projected a sufficient distance for engaging the strip 5, I provide a pin retaining member 6 which is preferably formed from a single piece of spring wire of suitable size and which, at a suitable position near one end is bent to form a pin receiving coil 7. The end of the wire at the inner end of the coil is bent back alongside of and at a suitable angle from the coil 7 and is then bent inwardly near the outer end of the coil to form a stop shoulder 8 after which this end of the wire is again bent outwardly at substantially right angles to the shoulder 8 and has its extremity bent into the form of an eye 9 which provides a handle for this end of the wire.

The end of the wire at the outer end of the coil is bent at right angles to the coil to form a laterally projecting stop loop 10 after which the wire is again bent inwardly alongside of the coil and to a slight distance beyond the inner end thereof to form a spring arm 11 at the inner end of which the wire is bent to form two or more pin engaging coils 12. After forming the coils 12 the wire is bent back to form a spring arm 11' corresponding to the spring arm 11 and, at a point opposite the stop shoulder 8 in the said arm 11, the wire is bent inwardly to form a stop shoulder 13. After forming the shoulder 13 the end of the wire is extended

outwardly and has formed on its outer end an eye 14 which provides a handle for this end of the wire corresponding to the handle 9 on the opposite end thereof.

- 5 It will be noted that the stop shoulders 8 and 13 in the ends of the wire are disposed a short distance inwardly from the laterally projecting stop loop 10 whereby when the retainer is projected through the eye 2 in 10 the hat crown the shoulders 8 and 13 will engage the inner side of the eye, while the stop loop 10 will engage the outer side thereof, thus locking the retainer in the eyelet or preventing any lateral movement of 15 the retainer after the same has been engaged with the eyelet. In thus engaging the retainer with the eyelet the handles 9 and 14 are gripped and drawn together thus retracting the shoulders 8 and 13 and the 20 spring wire arms on which they are formed, so that the inner portion of the retainer may be readily projected through the eyelet until the stop loop 10 comes into engagement with the outer side of the eyelet after which the 25 handles 9 and 14 are released and the shoulders 8 and 13 thus permitted to spring out into engagement with the inner side of the eyelet as clearly shown in Figs. 2 and 3 of the drawings.
- 30 In engaging the retainer with the pin the latter is projected through the coil 7 and into engagement with the coils 12 on the spring arm 11, said arm being first depressed to bring the coils 12 in line with the coil 7.
- 35 After the retainer has thus been engaged with the pin and adjusted to the desired position thereon the spring arm is released so that the pressure thereof will draw the coils 12 into tight frictional engagement with the 40 pin and will also bind the pin against the inner sides of the coil 7 thereby holding the retainer in tight frictional engagement with the pin in the position to which the retainer has been adjusted on the pin. The retainer 45 when thus placed upon the pin will be adjusted a sufficient distance from the point thereof so that when the point of the pin is in engagement with the strip 5 in the crown of the hat, the retainer will be in position 50 to engage and grip the eyelet in the manner described so that thereafter when the pin is inserted in the hat until the retainer comes into engagement with the eyelet and the point of the pin in engagement with the 55 strip 5, the inward movement of the pin will be stopped and the pin thus prevented from being projected through the opposite side of the crown of the hat as will be readily understood. The engagement of the 60 retainer with the eyelet in the manner described will also prevent the casual disengagement of the pin from the hat so that the pin will not come out until the handles 9 and 14 of the retainer are brought together 65 and the stop shoulders 8 and 13 thus re-

tracted a sufficient distance to permit their passage through the eyelet as will be readily understood.

Having thus described my invention, what I claim is:

1. A hat pin retainer adapted to be inserted in an opening in the crown of a hat and comprising a pin receiving element adapted to pass through said opening in the hat, a stop at one end of said element to engage one side of the hat, a yielding stop member carried by said element and adapted to spring into engagement with the opposite side of the wall of the hat, whereby the retainer will be held in position and means carried by said element and coacting therewith to grip the pin inserted in it and thereby retain the pin in said element. 70

75 2. In a hat pin retainer, an eyelet adapted to be secured in the crown of a hat, a retaining member comprising a pin receiving element adapted to be engaged with the pin, a stop arranged at one end of said pin receiving element and to engage the outer side of 80 said eyelet when the pin is inserted therethrough, yielding stop members carried by 85 said pin receiving element and adapted to spring into engagement with the inner side of the eyelet when the pin is inserted therethrough whereby the pin is held against 90 lateral movement in either direction, and means carried by said pin receiving element and co-acting therewith to grip the pin and thereby firmly secure said element in position on the pin. 95

100 3. A hat pin retainer comprising an eyelet adapted to be secured in one side of a hat crown, a pin retaining member formed from a piece of spring wire bent to form a pin receiving coil having at one end a laterally projecting stop loop adapted to be engaged with the outer side of said eyelet when the pin and coil are inserted therethrough, a spring arm formed on one end of the wire and having therein an offset shoulder to 105 engage the inner side of the eyelet, a pin gripping member comprising coils formed in the other end of the wire and adapted to be sprung into alignment with the pin receiving coil and to receive and grip the pin when inserted through the latter thereby holding the retainer in its adjusted position on the pin, a spring arm bent from the wire after forming said gripping coils, said arm having an offset shoulder also adapted 110 to engage the inner side of the eyelet, said eyelet engaging shoulders co-acting with said stop loop to hold the retaining member in engagement with the eyelet and the pin in position in the crown of the hat, and 115 handles formed on the outwardly projecting extremities of the ends of the wire to retract said stop shoulders whereby the retaining member and pin may be disengaged 120 from the eyelet in the hat. 125

4. A hat pin retainer comprising a pin receiving coil to enter an opening in the crown of a hat, means connected with said coil to engage the opposite sides of the wall of a hat crown to retain said coil in position, a pin gripping coil movable into and out of longitudinal alinement with the pin receiving coil, and a spring arm connecting said coils.
- 10 5. A hat pin retainer comprising a pin receiving element, a pin locking element adapted to receive the pin and to be moved into and out of longitudinal alinement with said pin receiving element, means connecting said elements for movement with respect
- 15 to each other and holding them normally out of alinement, a stop carried by said pin receiving element, a removable catch carried by the pin receiving element and spaced from said stop whereby the latter and the catch are adapted to detachably fasten the device to a supporting structure.
- In testimony whereof I have hereunto set my hand in the presence of two subscribing witnesses.

JOHN BOLAND.
